BOBBIN WINDER FOR SEWING MACHINES

Sidney J. Hamlett, Jr., Parma, Ohio, assignor to
White Sewing Machine Corporation, Cleveland,
Ohio, a corporation of Delaware

Application April 10, 1944, Serial No. 530,245

8 Claims. (Cl. 112—218)

1

The present invention relates to sewing machines and, more particularly, to a bobbin winder for sewing machines.

The object of the present invention is the provision of a novel and improved bobbin winder for sewing machines, which bobbin winder will be simple and compact in construction, reliable in operation, automatically actuated to disconnect the drive to the bobbin when a predetermined amount of thread has been wound thereon, and adaptable to be enclosed in a sewing machine proper in such a manner that it is readily available for use.

Another object of the invention is the provision of a novel and improved bobbin winder for sewing machines, which bobbin winder comprises a driven element carried by a member adapted to be supported from a stationary part of a sewing machine in such a manner that the driven element can be engaged with and disengaged from a movable element of the sewing machine so as to rotate a bobbin attached to the bobbin winder or stop the rotation thereof, in combination with means for positively moving the member in a direction to disengage the driven element from its driving element when a predetermined amount of thread has been wound on the bobbin.

Another object of the invention is the provision of a novel and improved bobbin winder for sewing machines comprising a driven element carried by an assembly adapted to be supported from a stationary part of a sewing machine in such a manner that the driven element can be engaged with and disengaged from a movable element of the sewing machine so as to rotate a bobbin attached to the bobbin winder or stop the rotation thereof, in combination with means for positively moving the bobbin winder assembly in a direction to disengage the driven element from its driving movable element when a predetermined amount of thread has been wound on the bobbin, and including a lost motion connection between two relatively movable parts of the winder assembly, which lost motion connection comprises resilient means for continuously urging the driven element in a direction towards the driving movable element.

Another object of the invention is the provision of a novel and improved sewing machine including a bobbin winder adapted to be driven from a movable element of the sewing machine and automatically disconnected therefrom when a predetermined amount of thread has been wound on a bobbin attached thereto, which bobbin winder is compact in construction, reliable in operation, and incorporated in the sewing machine in such a manner that it is enclosed within the sewing machine proper while being readily accessible for use.

Another object of the invention is the provi-

2

sion of a novel and improved sewing machine comprising a bobbin winder adapted to be driven from a movable element of the sewing machine and automatically disconnected therefrom when a predetermined amount of thread has been wound on a bobbin attached thereto, which bobbin winder is compact in construction, reliable in operation, and incorporated in the sewing machine in such a manner that it is normally housed within the sewing machine proper but movable to project the bobbin carrying spindle or portion thereof outside of the sewing machine housing or frame for the purpose of connecting and/or disconnecting a bobbin therewith.

15 The invention resides in certain constructions and combinations and arrangements of parts and further objects and advantages thereof will be apparent to those skilled in the art to which it relates from the following description of the preferred embodiments thereof described with reference to the accompanying drawings, forming a part of this specification, in which similar reference characters designate corresponding parts, and in which:

20 Fig. 1 is a fragmentary front elevational view of a sewing machine embodying the present invention;

Fig. 2 is an enlarged view of a portion of Fig. 1 with the closure for the bobbin winder open and with portions shown in section approximately on the lines 2—2 of Figs. 3 and 4;

Fig. 3 is a bottom view of the mechanism shown in Fig. 2;

Fig. 4 is an end view, looking from the right, of the mechanism shown in Fig. 2;

Fig. 5 is a fragmentary plan view of the horizontal portion of the gooseneck of a sewing machine showing a modification of the bobbin winder shown in Figs. 1 to 4, inclusive;

40 Fig. 6 is a sectional view approximately on the line 6—6 of Fig. 5; and

Fig. 7 is a sectional view approximately on the line 7—7 of Fig. 5.

While the invention is susceptible of various embodiments and alternative constructions, the preferred construction is herein shown and described as embodied in a sewing machine similar to the sewing machine disclosed in my copending application, Serial No. 525,023, filed the 4th day of March, 1944. Only those parts of the sewing machine proper which are necessary to a complete understanding of the present invention are herein shown and described in detail.

Referring to Figs. 1 to 4, inclusive, of the drawings and particularly to Fig. 1, the sewing machine shown therein comprises a horizontal bedplate A having a bracket or gooseneck B at the upper side thereof, which parts constitute the frame or housing of the sewing machine head and are adapted to be mounted in a suitable cabinet,

as is well understood in the art. The sewing mechanism per se forms no part of the present invention and may be of any conventional construction. Suffice it to say that the conventional sewing mechanism shown includes a main or needle bar shaft rotatably supported in the upper horizontal portion of the gooseneck B, and a main connecting assembly and a feed actuating mechanism for operatively connecting the main shaft with the sewing mechanism located underneath the bed plate A.

In the embodiment shown, the sewing mechanism is actuated by an electric driving motor 13 mounted on the underside of the bedplate A and operatively connected to the main shaft 10 by means including a V-belt drive, designated generally by the reference character C. The particular drive employed forms no part of the present invention but is preferably that disclosed and claimed in my aforesaid application. The driving motor 13, as shown, is operatively connected by a flexible shaft 14 of commercial construction, to a shaft 15 rotatably supported in a bracket 16 projecting from the underside of the bedplate A. The driving pulley 17 of the V-belt drive C is keyed or otherwise suitably fixed to the shaft 15, the projecting right hand end of which is provided with a friction wheel 18.

Generally speaking, the bobbin winding mechanism of the present invention comprises a bobbin winder assembly enclosed or adapted to be enclosed within a sewing machine and including two members having limited relative movement with respect to each other pivotally connected or adapted to be pivotally connected to a stationary part of the sewing machine in such a manner that a driven element connected to a bobbin carrying spindle may be moved into and out of driven engagement with a movable element of the sewing machine, in combination with resilient means for continuously urging the driven element carrying member of the bobbin winder assembly with respect to the other of the first named members in a direction to engage the driven element with its driving element and resilient means controlled by the amount of thread on the bobbin being wound for moving the driven element out of contact with its driving element.

Referring to the embodiment shown in Figs. 1 to 4, inclusive, of the drawings, the bobbin winder assembly is designated generally by the reference character D and comprises the two relatively movable members 20 and 21 pivotally connected by a screw 22 to a bracket E detachably secured to the underside of the bedplate A. The free end of the member 20 is provided with a transversely extending shaft 23, the rear end of which, as viewed in Figs. 1 and 2 is provided with a driven friction wheel 24 adapted to engage the driving friction wheel 18 previously referred to. The opposite or front end 25 of the shaft 23 is hollow and split longitudinally to form a resilient spindle adapted to receive a bobbin F. Both of the members 20 and 21 are irregular in shape and the member 20 is provided with approximately a right angle bend intermediate the ends thereof, the construction being such that as the winder assembly is rotated about the screw 22 as a pivot, the free end thereof and, in turn, the spindle 23 upon which the bobbin to be wound is mounted is moved into and out of an aperture 26, in the bedplate A, which aperture is adapted to be normally closed by a cover or door 27 hinged as by the arms 30, 31 and a pintle pin 32 to the bracket E. A spring 33 encircling the pintle pin 32 moves

the cover or door 27 to open position and holds the same open. Any suitable means may be employed for normally holding the cover or door 27 in position to close the aperture 26. The bracket E comprises two downwardly extending flanges 34, 35 and the pintle pin 32 is fixed in suitably aligned apertures therein. The screw 22, previously referred to, is fixed to the smaller rear flange 35.

10 The bobbin winder assembly D is continuously urged in a counterclockwise direction, as viewed in Fig. 2, by a coil spring 36, surrounding the hub 37 of the member 20, opposite ends 40 and 41 of which spring engage the underside of the bracket E and a horizontally extending projection 42 on the member 21. The member 20 is continuously urged in a clockwise direction, as viewed in Fig. 2, with respect to the member 21 by a coil spring 43, opposite ends 44 and 45 of which spring engage the members 20 and 21 respectively. However, relative movement between the members 20 and 21 in a clockwise direction, as viewed in Fig. 2, under the action of the spring 43 is limited by the horizontal projection 42 previously referred to. In the embodiment shown, relative movement between the members 20 and 21 in the opposite direction, that is, counterclockwise as viewed in Fig. 2, is limited by an irregularly-shaped arm or member 46 formed integral with the right hand end of the member 21. The arm 46 projects to the right above the end of the member 20. The members 20 and 21 are so constructed as to permit a limited movement of the member 20 relative to the member 21 between the stops 42 and 46. The highest part of the arm 46 forms an abutment for the bobbin winder assembly D when the aperture 26 is closed by the cover 27, as will be hereinafter more specifically described.

While a bobbin is being wound the bobbin winder assembly D is held in the position shown in Fig. 2, with the driven friction wheel 24 in engagement with the driving member or wheel 18, by a latch designated generally by the reference character G, which latch is pivotally connected to the flange 34 by a screw 47 and comprises a projection 48 adapted to engage over a pin 50 formed integral with the member 21 of the bobbin winder assembly D. The latch G is continuously urged in a counterclockwise direction, as viewed in Fig. 2, to engage the projection 48 over the pin 50, by a tension spring 51 connected to an arm 52 thereof and to a pin 53 projecting inwardly from the flange 34. In addition to the parts previously mentioned, the latch G comprises an elongated arm 54 the intermediate portion of which extends between the flanges of the bobbin F and is adapted to be moved radially of the bobbin by thread wound thereon.

The construction is such that the latch G is so moved by the engagement of the elongated arm 54 with the thread being wound on the bobbin that the projection 48 is disengaged from the pin 50, and the winder assembly D thereby released when a predetermined amount of thread has been wound upon the bobbin. Upon being released from the latch G, the winder assembly D moves into the dot-dash line position shown in Fig. 2 under the action of the spring 36. Movement of the winder assembly D under the action of the spring 36 is limited by the engagement of a projection 55 on the member 21 with the underside of the bed plate A. Alternately, the projection 55 may engage the bracket E.

Because of the lost motion connection, including the spring 43, between the members 20

and 21 of the bobbin winder assembly D, the friction wheel 24 is yieldably engaged with the driving member 18 when the winder assembly is latched in the position shown in Fig. 2. Attention is called to the fact that the springs 36 and 43 both encircle the pivot upon which the members 20 and 21 are rotatably supported. This arrangement provides a simple and compact construction.

When the device is not in use, it is housed underneath the bed plate A and in order to eliminate any possibility of the friction wheels 18 and 24 being in contact with each other when the cover 27 is closed, the projecting end 56 of the elongated arm 54 of the latch G is adapted to be depressed sufficiently to hold the projection 48 of the latch G clear of the pin 50 upon the closing of the cover 27 by a rod 57 slidably supported in vertically spaced projections 60 and 61 formed integral with the flange 34. The lower end of the rod 57 is adapted to engage the upper surface of the end of the arm 54 and the upper end thereof is provided with a head 62 adapted to be engaged by the under side of a cover 27 as the cover is moved into closed position. The rod 57 is continuously urged in an upward direction by a coil spring 63 surrounding the same and interposed between the upper side of the projection 61 and a collar 64 fixed to the rod 57 below the projection 60. When the cover 27 is closed the rod 57 is depressed and the latch G held in inoperative position, as previously stated. At this time the highest portion of the arm 48 engages the underside of the cover 27 and the various parts are in the position shown in Fig. 1. A projecting member 65 on the underside of the cover 27 and provided with an aperture 66 forms a guide for thread being wound upon the bobbin.

It is believed that the operation of the device will be apparent from the foregoing description thereof. Suffice it to say that when the cover 27 is released it moves into open position, that is, into the position shown in Fig. 2, whereupon the winder assembly D moves to loading position which is the position shown in dot-dash lines in Fig. 2. It will be observed that the bobbin receiving spindle of the bobbin winder assembly is above the bed plate A and without the housing of the sewing machine proper; in other words, the spindle is so positioned that a bobbin can be readily attached to or detached from the bobbin carrying portion 25 of the spindle 23. After the bobbin has been positioned upon the end 25 of the spindle 23, the assembly is manually moved in a clockwise direction about the pivot 22 until the projection 48 of the latch G engages over the pin 50 on the member 21. This movement of the bobbin winder assembly D moves the friction wheel 24 into engagement with the driving member 18. The motor 15, if not already in operation, is then started.

When a predetermined amount of thread has been wound on the bobbin F the pin 50 is automatically released from the latch G, whereupon the bobbin winder assembly D will move to the position shown in dot-dash lines in Fig. 2 under the action of the spring 36. The wound bobbin is then removed, whereupon the cover or door 27 can be closed. As the door 27 closes, the bobbin winder assembly D is moved to the position shown in Fig. 1. If for some reason the bobbin winder assembly D happens to be in the position shown in full lines in Fig. 2, when the door 27 is closed, the engagement of the head 62 of the pin 57 therewith will move the latch G to release

the winder assembly D, whereupon the winder assembly will move in a counterclockwise direction until the arm 46 strikes the underside of the cover 27.

5 The bobbin winder of the present invention is shown in Figs. 1 to 4, inclusive, as located underneath the bed plate of a sewing machine, however, it is to be understood that the bobbin winder of the present invention may be located at other convenient places about the machine, for example, in either the column or the horizontal arm of the gooseneck.

An embodiment of the invention showing the bobbin winder in the horizontal arm or portion 15 of the goose neck of a sewing machine is shown in Figs. 5, 6 and 7. Referring to these figures, the bobbin winder proper is located within an aperture formed in the top of the gooseneck B'; which aperture is adapted to be closed by a door or cover 16 hinged at its rear to the frame proper. In this embodiment the bobbin winder assembly D', comprising the relatively movable co-axially pivoted arms or members 120 and 121, is pivotally connected by a screw 122 to a bracket E' fixed to a web 11 formed integral with the gooseneck B' of a sewing machine head in such a way that the driven friction wheel 124 fixed to the bobbin carrying spindle 123 rotatably supported in the free end of the member 120 is adapted to be engaged with and disengaged from a driving friction wheel 118 carried by the main shaft 119 of the sewing machine. Alternatively, the friction wheel 124 may contact some other rotatable part of the sewing machine.

20 25 30 35 40 45 50 55 60 65 70 75 The bobbin winder assembly D' is continuously urged in a counterclockwise direction as viewed in Fig. 6 to project the bobbin carrying spindle 123 thereof above the arm B' by a coil spring 136 encircling the hub of the member 120, opposite ends 140, 141 of which spring are connected to the bracket E' and the member 121, respectively. Movement of the member 120 relative to the member 121 is limited by flanges 142, 146, formed integral with the member 121 and projecting below and above the arm or member 120. The space between the projections 142, 146, is slightly greater than the height of the arm 120, permitting a slight relative movement between the members 120 and 121. The member 120 is continuously urged in a counterclockwise direction as viewed in Fig. 7 with respect to the member 121 by a coil spring 143 also surrounding the hub of the member 120, opposite ends 144, 145 of which are connected to the member 120 and the underside of the member 121, respectively. The screw 122 which forms the pivot for the bobbin winder assembly D' is fixed in a flange 135 formed integral with the bracket E'. The flange 135 also includes an inwardly extending projection 12 adapted to be engaged by the arm 120 to limit the rotation of the assembly D' in a counterclockwise direction as viewed in Fig. 6.

For the purpose of winding a bobbin, the winder assembly D' is held in the position shown in full lines in Fig. 6, with the driven friction wheel 124 in engagement with the driving wheel 118 by a latch G', similar in construction to the latch G previously referred to, and comprising a projection 148 adapted to engage over a pin 150 fixed to the member 121. The latch G' is pivotally connected to an upstanding flange 134 on the bracket E' by a headed pin 147 and is continuously urged in a counterclockwise direction as viewed in Fig. 6 by a vertically positioned tension spring 151 connected to an arm 152 thereof and

to the bracket E'. The latch G' is also provided with a forwardly extending arm 154 adapted to extend between the flanges of a bobbin F' positioned on the bobbin receiving end 125 of the spindle 123 and engage thread wrapped upon the bobbin and be moved thereby.

The thread guide 73 fixed to the underside of the cover 70 serves the same function as the rod 57 in the embodiment shown in Figs. 1 to 4, inclusive, and is so constructed that when the cover 70 is closed, the lower end thereof engages the projecting arm 154 of the latch G' and holds the latter in an inoperative position, thus eliminating any possibility of the friction wheels 118 and 124 being in contact when the cover is closed. The friction wheels 118 and 124 are small metal hubs provided with rubber tires, whereas the friction wheels shown in Figs. 1 to 4, inclusive, are cone-shaped or beveled wheels, however, it is to be understood that any suitable type of friction wheel may be employed.

The operation of the device shown in Figs. 5, 6, and 7 is as follows: When it is desired to wind a bobbin the cover 70 is raised to the position shown in Fig. 7. Prior to the raising of the cover 70, the bobbin winder assembly D' is in the lower dot-dash line position shown in Fig. 7, with the top of the wheel 124 engaging the underside of the cover 70. When the cover 70 is raised, the assembly moves to the upper dot-dash line position shown in Fig. 7 under the action of the spring 136. While the assembly is in its raised or upper position, the bobbin to be wound is placed on the bobbin-receiving portion 125 of the spindle 123. After the end of the thread is secured to the bobbin, the bobbin winder assembly D' is manually moved in a downward direction until the pin 150 is engaged by the latch G', which is the position shown in Fig. 7, with the friction wheels 118, 124 in contact with each other. When the bobbin is placed on the spindle 123, the projecting arm 154 of the latch G' is positioned between the flanges thereof and after a predetermined amount of thread is wound upon the bobbin, the latch G' is moved clear of the pin 150, whereupon the bobbin winder assembly automatically moves to the upper dot-dash line position shown in Fig. 7. After the bobbin is removed, the cover 70 is again closed.

From the foregoing disclosure of the invention and the description of the preferred embodiments shown, it will be apparent that the objects herefore enumerated and others have been accomplished and that a new and improved bobbin winder for sewing machines has been provided as well as a new and improved sewing machine.

Two preferred embodiments of the invention have been illustrated and described with considerable detail, however, the invention may be otherwise embodied and numerous changes may be made in the construction shown within the scope of the invention, and it is to be understood that I do not wish to be limited to the particular embodiments or constructions shown, but it is my intention to hereby cover all adaptations, modifications and uses of the devices shown which come within the practice of those skilled in the art to which the invention relates and within the spirit and scope of the appended claims.

Having thus described my invention I claim:

1. In a sewing machine, the combination of: a bed plate having an aperture therein, sewing mechanism including a movable element located underneath said bed plate; a bobbin winder assembly comprising a movable member, a shaft

adapted to have a bobbin detachably secured thereto, means for rotatably supporting said shaft in said movable member, and a driven element fixed to said shaft and adapted to be moved into and out of driven engagement with said movable element; means for movably supporting said bobbin winder assembly underneath said bed plate for movement of said shaft to a position beneath the bed plate with said driven element in operative engagement with said movable element or outwardly through said aperture to a position above said bed plate where it is accessible to have a bobbin removed therefrom or placed thereon; and a movable cover for said aperture which when in closed position maintains said shaft below said bed plate.

2. In a sewing machine, the combination of: a bed plate having an aperture therein; sewing mechanism including a movable element located underneath said bed plate, a bobbin winder assembly comprising a movable member, a shaft adapted to have a bobbin detachably secured thereto, means for rotatably supporting said shaft in said movable member, and a driven element fixed to said shaft and adapted to be moved into and out of driven engagement with said movable element; means for pivotally supporting said bobbin winder assembly underneath said bed plate for movement of said shaft to a position beneath the bed plate with said driven element in operative engagement with said movable element or outwardly through said aperture to a position above said bed plate where it is accessible to have a bobbin removed therefrom or placed thereon; and a movable cover for said aperture which when in closed position maintains said shaft below said bed plate.

3. In a sewing machine, the combination of: a bed plate having an aperture therein, sewing mechanism including a rotatable element located underneath said bed plate; a bobbin winder assembly comprising a movable member, a shaft adapted to have a bobbin detachably secured thereto, means for rotatably supporting said shaft in said movable member, and a driven element fixed to said shaft and adapted to be moved into and out of driven engagement with said rotatable element; means for pivotally supporting said bobbin winder assembly underneath said bed plate for movement about a horizontal axis whereby said shaft may be moved to a position beneath the bed plate with said driven element in operative engagement with said rotatable element or outwardly through said aperture to a position above said bed plate where it is accessible to have a bobbin removed therefrom or placed thereon; and a movable cover for said aperture which when in closed position maintains said shaft below said bed plate.

4. In a sewing machine, the combination of: a bed plate having an aperture therein; a movable cover for said aperture; sewing mechanism including a movable element located underneath said bed plate; a bobbin winder assembly comprising two relatively movable members, a shaft adapted to have a bobbin detachably secured thereto, means for rotatably supporting said shaft in one of said members, a driven element fixed to said shaft and adapted to be moved into and out of driven engagement with said movable element, and means including a lost motion operative connection between said members; means for pivotally supporting said bobbin winder assembly underneath said bed plate; resilient means continuously urging said bobbin winder

assembly in a direction to move said shaft outwardly through said aperture and said driven element away from said movable element; said cover when in closed position maintaining said assembly beneath said bed plate, said bobbin winder assembly comprising resilient means interposed between said members for yieldably urging said driven element in a direction towards said movable element; movable means mounted independently of said members for holding said bobbin winder assembly against the action of said first named resilient means in a position in which said driven element engages and is driven by said movable element; and means controlled by the amount of thread on a bobbin supported on said shaft for moving said movable means to release said bobbin winder assembly to move said shaft when said cover is in open position outwardly of said aperture to a position accessible for removing the wound bobbin therefrom and placing an empty bobbin thereon.

5. In a sewing machine, the combination of: a bed plate having an aperture therein; a movable cover for said aperture; sewing mechanism including a rotatable element located underneath said bed plate; a bobbin winder assembly comprising two relatively rockable members, a shaft adapted to have a bobbin detachably secured thereto, means for rotatably supporting said shaft in one of said members, a driven element fixed to said shaft and adapted to be moved into and out of driven engagement with said rotatable element, and means comprising a lost motion operative connection between said members and including resilient means interposed between said members for yieldably urging said driven element in a direction towards said rotatable element of said sewing mechanism; means for pivotally supporting said bobbin winder assembly underneath said bed plate; resilient means for continuously urging said bobbin winder assembly in a direction to move said shaft outwardly through said aperture and said driven element away from said rotatable element; movable means for holding said bobbin winder assembly against the action of said last named resilient means in a position in which said driven element engages said rotatable element of said sewing mechanism; means controlled by the amount of thread on a bobbin supported on said shaft for moving said movable means to release said bobbin winder assembly; and means operatively connected to said cover for actuating said movable means in a direction to release said bobbin winder assembly when said cover is moved to close said aperture.

6. In a sewing machine, the combination of: a bed plate having an aperture therein; a movable cover for said aperture; sewing mechanism including a movable element located underneath said bed plate; a bobbin winder assembly comprising two relatively rockable members; a shaft adapted to have a bobbin detachably secured thereto, means for rotatably supporting said shaft in one of said members, a driven element fixed to said shaft and adapted to be moved into and out of driven engagement with said movable element, and means comprising a lost motion operative connection between said members and including resilient means urging said driven element in a direction towards said movable element of said sewing mechanism; means for pivotally supporting said bobbin winder assembly underneath said bed plate; resilient means continuously urging said bobbin winder assembly in a direction to move said shaft outwardly through

said aperture and said driven element away from said movable element; movable means for holding said bobbin winder assembly against the action of said second named resilient means in a position in which said driven element engages and is driven by said movable element; means controlled by the amount of thread on a bobbin supported on said shaft for moving said movable means to release said bobbin winder assembly; and means operatively connected to said cover for moving said movable means to releasing position when said cover is moved to close said aperture.

7. In a sewing machine, in combination, a frame member having an aperture therein, a movable cover for closing said aperture, sewing mechanism including a moving driving part located within said frame member; a bobbin winding device comprising a pair of members, means secured to said frame member for coaxially supporting said pair of members for rocking movement from one side of said aperture to the other side thereof, means forming a lost motion operative connection between said rocking members, a shaft rotatably supported by one of said rocking members and adapted to have a bobbin detachably secured thereto, a driven element fixed to said shaft and engageable with said driving part, resilient means yieldingly urging said one rockable member in a direction to engage said element with said driving part, a separate resilient means urging the other of said rocking members in a direction to disengage said element from said movable part and to move said rocking members in one direction through said aperture, latch means for holding said other rockable member against movement by said separate resilient means, and means controlled by the amount of thread on the bobbin for releasing said latch means; and cooperating means operatively associating said cover and said latch releasing means when the cover is in aperture closing position to maintain said releasing means in latch released position.

45 8. In a sewing machine, in combination, a gooseneck having an aperture in the horizontal arm thereof and a cavity underlying said aperture, a movable cover for closing said aperture, sewing mechanism including a moving driving part located within said horizontal arm; a bobbin winding device comprising a pair of members, means secured to said horizontal arm in the cavity thereof and coaxially supporting said members for rocking movement, means forming a lost motion operative connection between said rocking members, a shaft rotatably supported by one of said rocking members and adapted to have a bobbin detachably secured thereto, a driven element fixed to said shaft and adapted to engage

50 and be driven by said movable part, resilient means yieldingly urging said one member in a direction to engage said element with said movable part, a separate resilient means urging the other of said rocking members in a direction to disengage said element from said movable part and move both of said members through said aperture, latch means for holding said members against movement by said resilient means, and means controlled by the amount of thread on the bobbin for releasing said latch means; said cover being provided with a depending portion cooperating with said latch releasing means when the cover is in aperture closing position to maintain said releasing means in latch released position.
